erence should be had to the accompanying drawings and descriptive matter in which I have illustrated and described a preferred embodiment of my invention.

In the drawings:

5 Fig. 1 is a sectional elevation of a steam generating unit embodying my invention.

Fig. 2 is a sectional plan taken on the line 2—2 of Fig. 1.

10 Fig. 3 is a sectional elevation taken on the line 3—3 of Fig. 1.

Fig. 4 is a sectional elevation taken on the line 4—4 of Fig. 1.

15 Fig. 5 is a sectional elevation taken on the line 5—5 of Fig. 1.

Fig. 6 is a sectional plan view similar to Fig. 2 of a modified form of the invention.

The boiler unit illustrated comprises a setting of rectangular cross-section having upright front and rear walls

20 10 and 12, respectively, upright side walls 14 and 16, an upper enclosing wall or roof 18 and a lower enclosing wall or floor 20. The space within the setting is divided by a partition wall 22 to provide a boiler tube space 24 laterally adjoining a furnace chamber 26. The pressure parts of the boiler include upper and lower

25 drums 28 and 30, respectively, which extend the full length of the setting in parallel offset relation, and are connected by a bank of upright boiler tubes 32 disposed within the boiler tube space 24 and having their ends radially connected to the drums. The drum 28 is also

30 interconnected to the drum 30 by downcomer pipes 34 and 36 located externally of the front and rear walls 10 and 12, respectively.

35 The partition wall 22 is formed by a row of tubes 38 which are partially studded to support refractory closing

the intertube spaces throughout their extent. This wall extends from the rear wall 12 to a location spaced from the front wall 10 whereby a gas outlet 40 is provided for heating gases flowing from the furnace chamber 26

40 into the boiler tube space 24. Tubes 42 are spaced and arranged to provide a screen across the gas outlet 40.

The furnace chamber 26 is fluid cooled by a row of tubes 44 extending along the floor 20, side wall 14 and roof 18 between the upper and lower drums 28 and 30, respectively; a row of tubes 46 extending along the rear

45 wall 12 between a lower header 48 and an upper header 50, the lower header being connected to the drum 30 through supply tubes (not shown) and the upper header being connected to the drum 28 through riser tubes (not shown); and a row of tubes 52 extending along the front

50 wall 10 between headers (not shown) connected into the circulation system in the same manner as that described for the rear wall. The furnace chamber portions of all these wall tubes are studded and covered with refractory.

55 Transverse baffle walls 54 and 56 extending partially across boiler tube space 24 and a partition wall 58 provide serially connected gas passes 60, 62, and 64 through

which a substantially horizontal flow of heating gases is maintained from the furnace chamber 26, the gases

60 from the final pass 64 being discharged from the setting through a boiler gas outlet 66 which terminates at damper 68.

The portion of wall 10 defining the front section of the open gas passage 60 is fluid cooled by a row of studded

65 and refractory covered tubes 70. The baffle wall 54 extends downwardly throughout the height of the boiler tube space 24 and laterally from the front end of the partition wall 22 to a point spaced from the partition wall

58. The baffle wall 56 is positioned rearwardly of the baffle wall 54 and extends from the rear wall 16 across

70 the boiler tubes 32 to a position spaced from the partition wall 22. Some of the boiler tubes 32 are formed

This invention relates in general to steam generators, and more particularly, to steam generating and superheating units of the type especially adapted for use in marine installations and including provisions for regulating the flow of heating gases over the steam superheating surface to control the heat absorption thereof.

In a steam generating and superheating unit of the type of the invention, the amount of convection heated steam superheating surface is proportioned and arranged to provide a predetermined final steam temperature at the steam outlet at a predetermined load. As the prime mover associated with such a unit is generally designed for operation with a maximum steam temperature at the predetermined load, provisions are normally made for maintaining the steam temperature at the desired value at loads in excess of the predetermined load by controlling the flow of heating gases over the steam superheating surface.

Heretofore, the practice in effecting superheat control in marine installations has been to provide parallel damper-controlled gas passages and to confine the steam superheating surface wholly or substantially wholly to one of the gas passages. However, the provision of parallel gas passages results in restriction of the width of each pass and with the usual form of superheater comprising looped tubes extending between upright headers, the surface available for superheating may be inadequate for attainment of the degree of superheat desired. Moreover, the restriction of the cross-sectional area of each passage results in a relatively high draft loss.

In accordance with the present invention a steam generating and superheating unit of the general character described is constructed with a particular arrangement of convection heated steam superheating surface, whereby the unit can be operated to maintain a relatively low draft loss and a substantially constant degree of superheat over a relatively wide steam generating load range.

The present invention provides a steam generating and superheating unit having a furnace chamber disposed at one side of a steam generating tube bank, and a superheater disposed within a superheater gas passage and at the side of the steam generating tube bank remote from the furnace chamber, while a substantially unobstructed or open gas passage is arranged to receive gases from the furnace chamber. Gases leaving the open gas passage normally flow partly to the space including the steam generating tube bank and partly to the superheater gas passage, which is of greater width than the open gas passage, in proportions determined by the steam load and the degree of superheat required. Means are also provided for variably proportioning the flow of gases to the steam generating tube bank and to the superheater surface.

The various features of novelty which characterize my invention are pointed out with particularity in the claims annexed to and forming a part of this specification. For a better understanding of the invention, its operating advantages and specific objects attained by its use, ref-

with intermediate bowed parts to provide the gas turning space between gas passes 62 and 64. The partition wall 58 extends longitudinally between an intermediate portion of the baffle wall 56 and the front wall 10.

Each of the baffle walls 54, 56, and the partition wall 58 is formed by at least one row of fluid cooled tubes 72, 74, and 76, respectively, which, with the exception of the lower portion of tubes 76, are studded to support refractory closing the intertube spaces. The intertube spaces of the lower part of wall 58 are left open to form a gas inlet 78 into an upright superheater gas passage 80. The baffle wall 56 and the partition wall 58 also serve to separate the boiler tube space 24 from the laterally adjoining superheater gas passage 80.

Wall tubes 38, 70, 72, 76 and screen tubes 42 are connected to drums 28 and 30, to provide natural circulation flow paths in parallel with the boiler tubes 32. The upper portions of some of the partition wall tubes 76 are formed with lateral extensions to screen the drum from radiation from the gases flowing through the boiler tube space 24. A part of the baffle wall tubes 74 are connected to drums 28 and 30, and the remainder extend from a lower header 82 to the drum 28, the header being connected to the drum 30 through a tubular connection 83.

The upright superheater gas passage 80 is of rectangular cross-section, and has boundary surfaces including portions of walls 10, 16, 56 and 58. The portion of the setting occupied by the gas passage 80 is advantageously employed for the location of the convection heated superheater surface of the unit. The superheater is of the drainable type and includes vertically spaced banks of multiple-looped horizontally arranged longitudinally extending tubular elements 84 disposed across the upward flow of gases and connected between horizontally arranged upper and lower headers 86 and 88, respectively. The superheater tubular elements 84 are suspended from structural steel work, adjacent loops being connected by means permitting differential expansion. The gases leaving the superheating gas passage 80 are discharged from the setting through a boiler gas outlet 90 which terminates at dampers 92.

As shown in Fig. 2, the superheater gas passage 80 extends outwardly beyond the front wall of the open gas passage 60, thus permitting installation of superheater tubes of substantial length and thereby facilitating the attainment of a high degree of superheat. Moreover, with the above described superheater gas passage and superheater construction and arrangement flexibility of design is permissible since the space available for the superheater may readily be varied by changing the distance between the partition wall 58 and the side wall 16.

Access to the tubes located adjacent the gas turning space between the gas passes 62 and 64 may be had through a door 94 situated in the rear wall 12. Access to the superheater gas passage 80 may be had through a door 96 located at the bottom of the front wall 10. In order to permit access also to the boiler tube space 24, three adjacent tubes 76a of the partition wall 58 are formed with lower end portions displaced laterally in the direction toward the rear wall 16. An access door 98 to the rear end of the gas pass 64 is provided in the side wall 16.

The unit is provided with an outer casing 100 which encloses the downcomer tubes and the superheater headers and defines a space for the flow of combustion air to burners 102.

Burners 102 of any suitable type are installed in association with the front wall 10 to provide a source of heating gases. The gases first pass substantially horizontally and rearwardly toward the rear wall 12 and then turn and flow forwardly to the outlet 40. The heating gases leave the furnace chamber 26 through the outlet 40 and then flow horizontally over the screen tubes 42 to the open gas passage 60. Gases leaving the open

gas passage 60 may divide so as to flow partly through the superheater gas inlet 78 and partly to the boiler tube space 24 in proportions determined by adjustment of dampers 68 and 92.

Gases entering the boiler tube space 24 flow horizontally over the boiler tubes 32 disposed in the gas passes 62 and 64 and then flow upwardly through the gas outlet 66 to the dampers 68. The gases which enter the superheater gas passage 80 have been cooled only to a limited degree and spread out in the space below the superheater, thus assuring uniform heating gas distribution to the superheater. Gases entering the superheater continue their upward flow across the tubes 84 and through the gas outlet 90 to the dampers 92. The dampers 68 and 92 control the gas flow through the superheater gas passage and through the boiler tube space, permitting variable proportioning of the gas flow to each section to provide an effective superheat control over a wide load range. These dampers may be automatically controlled for the purpose of maintaining a predetermined superheat temperature, by a control system which regulates the damper in accordance with the variations in the steam flow from the superheater outlet and also in response to variations in the superheat temperature from a predetermined value.

Header 86 receives steam from the drum 28 through tubular connections (not shown). The steam then flows from the header 86 through the superheater tubular elements 84 to the outlet header 88, and thence through a conduit (not shown) to the point of use.

Fig. 6 illustrates another form of the invention in which the baffle arrangement of Fig. 2 is modified so that the heating gases from the furnace chamber 26 make only a single pass over the tube bank 32. In this embodiment the partition wall 22 of Fig. 2 is omitted; the tube bank 32 and the superheater 84 are in the same relative positions as in Fig. 2; baffle wall 56A extends from the rear wall 16 to the rear end of baffle wall 58; baffle wall 54A extends transversely of the tube bank 32 adjacent the front end thereof; and a baffle wall 55 forms an angular continuation of baffle wall 56A and closes the space between baffle walls 56A and 54A. The baffle arrangement of Fig. 6 provides two parallel gas passes 60, 63 receiving gases from outlets 39 and 41, respectively, of the furnace chamber 26 and through which a substantially horizontal flow of heating gases is maintained from the furnace chamber 26. Each of the baffle walls 54A, 55, 56A is formed by at least one row of fluid cooled tubes 72A, 73, and 74A, respectively, which are studded to support refractory closing the intertube spaces. Tubes 43 are spaced and arranged to provide a screen across the gas outlets 39 and 41. The baffle wall tubes 72A and 73 and screen tubes 43 are connected at their opposite ends to drums 28 and 30 to provide natural circulation flow paths in parallel with the boiler tubes 32; and the baffle wall tubes 74A extend from the header 82 to the drum 28. Except for the features of difference mentioned above, and any necessary consequences thereof, the modified unit is to be assumed to be similar to the arrangement of Figs. 1 through 5.

The part of the superheater gas passage 80 containing the superheater 84 overlaps the part of the gas pass containing the tube bank 32. Although the cross-sectional area for gas flow of the open gas pass 60 is limited by the presence of the tube bank 32 to the rear thereof, which limits the length of the open gas pass 60, the cross-sectional area for gas flow of the superheater gas passage 80 is not limited for such a reason, and the cross-sectional area thereof has without difficulty been made relatively large, so that the draft loss through the unit due to the superheater is small having regard to the size of the superheater. Correspondingly, although the cross-sectional area for gas flow of the portion of the gas pass 63 to the rear of the superheater gas passage 80 is limited by the presence forwardly thereof of the super-

heater 84, which limits the length of said portion, the cross-sectional area for gas flow of the tube bank 32 is not limited for such a reason, and the cross-sectional area thereof for gas flow has therefore been made relatively large, so that the draft loss through the unit due to the tube bank is small having regard to the size of the tube bank.

In operation gases leaving the furnace chamber 26 flow in parallel paths to the gas passes 60 and 63. The portion of the gases entering gas pass 63 flow in a generally horizontal flow path over screen tubes 41 and boiler tubes 32 and then upwardly to the dampers 68; and the portion of the gases directed to the open gas pass 60 flow in a generally horizontal flow path over the screen tubes 41 and through the open gas pass 60 to the inlet 78 of the superheater gas passage 80 and thence upwardly across the superheater tubes 84 to the dampers 92. The proportions of the gases entering the gas passes 60, 63 are determined by adjustment of dampers 68 and 92.

While in accordance with the provisions of the statutes I have illustrated and described herein the best form of the invention now known to me, those skilled in the art will understand that changes may be made in the form of the apparatus disclosed without departing from the spirit of the invention covered by my claims, and that certain features of the invention may sometimes be used to advantage without a corresponding use of other features.

I claim:

1. A vapor generating and superheating unit comprising walls forming a setting containing pressure parts including horizontally disposed upper and lower drums and a bank of upwardly extending vapor generating tubes connected to said drums along the length thereof, some of said walls defining a furnace chamber laterally adjacent one side of the space containing said tube bank and communicating therewith at one end, means forming an upwardly extending superheater gas passage laterally adjacent the opposite side of the space containing said tube bank, a superheater disposed in said superheater gas passage and extending longitudinally of and in overlapping relation with said tube bank, baffle means including fluid cooled tubes arranged to divide the space containing said tube bank into a plurality of serially connected gas passes extending transversely of said tube bank and including an open gas pass between said drums opening to said superheater gas passage and receiving gases from said furnace chamber and to provide parallel gas flow paths from the open gas pass to the remainder of the serially connected gas passes and to the superheater gas passage, means for burning fuel in said furnace chamber and generating heating gases therein, and means for variably controlling the portion of the heating gases contacting with said superheater tubes to regulate the superheater heat absorption.

2. A vapor generating and superheating unit comprising walls forming a setting containing pressure parts including horizontally disposed upper and lower drums and a bank of vertically extending vapor generating tubes connected to said drums along the length thereof, some of said walls including fluid cooled tubes and defining a furnace chamber laterally adjacent one side of the space containing said tube bank and communicating therewith at one end, means forming an upright superheater gas passage laterally adjacent the opposite side of the space containing said tube bank, a bank of superheater tubes disposed across the flow of gases in said superheater gas passage and extending longitudinally of and co-extensively with a substantial portion of said tube bank, baffle means including fluid cooled tubes arranged to divide the space containing said tube bank into a plurality of serially connected gas passes extending transversely of said tube bank and including a substantially unobstructed gas pass between said drums opening to the lower portion of said superheater gas passage and receiving gases from said furnace chamber and to provide parallel gas flow paths from the open gas pass to the remainder of the serially connected gas

passes and to the superheater gas passage, means for burning fuel in said furnace chamber and generating heating gases therein, and means for variably controlling the portion of the heating gases contacting with said superheater tubes to regulate the superheater heat absorption.

3. A vapor generating and superheating unit comprising walls forming a setting containing pressure parts including horizontally disposed upper and lower drums and a bank of upwardly extending vapor generating tubes connected to said drums along the length thereof, some of said walls defining a furnace chamber laterally adjacent one side of said tube bank and arranged to discharge gases thereto, means forming an upwardly extending superheater gas passage laterally adjacent the opposite side of said tube bank and having a gas inlet, a superheater disposed in said superheater gas passage and extending longitudinally of and in overlapping relation with said tube bank, wall means including fluid cooled tubes arranged to divide the space containing said tube bank into a plurality of gas passes and forming parallel gas flow paths to said tube bank and to said superheater, said gas passes including a substantially unobstructed gas pass extending between said drums and opening at one end to said furnace chamber and at its opposite end to said superheater gas inlet, means for burning fuel in said furnace chamber and generating heating gases therein, and means for variably controlling the portion of the heating gases contacting with said superheater tubes to regulate the superheater heat absorption.

4. A vapor generating and superheating unit comprising walls forming a setting containing pressure parts including horizontally disposed upper and lower drums and a bank of upwardly extending vapor generating tubes connected to said drums along the length thereof, some of said walls including fluid cooled tubes and defining a furnace chamber laterally adjacent one side of the space containing said tube bank and arranged to discharge gases thereto, means forming an upwardly extending superheater gas passage laterally adjacent the opposite side of the space containing said tube bank and having a gas inlet, a bank of superheater tubes disposed across the flow of gases in said superheater gas passage and extending longitudinally of and co-extensively with a substantial portion of said tube bank, wall means including fluid cooled tubes arranged to divide the space containing said tube bank into a plurality of gas passes and forming parallel gas flow paths to said tube bank and to said superheater, said gas passes including a substantially unobstructed gas pass extending between said drums and opening at one end to said furnace chamber and at its opposite end to said superheater gas inlet, means for burning fuel in said furnace chamber and generating heating gases therein, and means for variably controlling the portion of the heating gases contacting with said superheater tubes to regulate the superheater heat absorption.

5. A vapor generating and superheating unit comprising walls forming a setting containing pressure parts including horizontally disposed upper and lower drums and a bank of vertically extending vapor generating tubes connected to said drums along the length thereof, some of said walls including fluid cooled tubes and defining a furnace chamber laterally adjacent one side of the space containing said tube bank and arranged to discharge gases thereto, means forming a vertically extending superheater gas passage laterally adjacent the opposite side of the space containing said tube bank and having a gas inlet in the lower portion thereof, a superheater including a bank of vertically spaced tubes disposed across the flow of gases in said superheater gas passage and extending in overlapping relation with a substantial portion of the length of said tube bank, wall means including fluid cooled tubes arranged to divide the space containing said tube bank into a plurality of gas passes and

forming parallel gas flow paths to said tube bank and to said superheater, said gas passes including a substantially unobstructed gas pass extending between said drums and opening at one end to said furnace chamber and at its opposite end to said superheater gas inlet, means for burning fuel in said furnace chamber and generating heating gases therein, and means for variably controlling the portion of the heating gases contacting with said superheater tubes to regulate the superheater heat absorption.

6. The vapor generating unit of claim 3 in which said fluid cooled wall means divides the space containing said tube bank into two gases passes and forms parallel gas flow paths to said tube bank and to said superheater,

one of said gas passes being substantially unobstructed and extending between said drums and opening at one end to said furnace chamber and at its opposite end to said superheater gas inlet.
